UNITED STATES PATENT OFFICE.

HUGO L. HILLER, OF NEW YORK, N. Y.

DESIGN FOR A SHOE-LACING.

SPECIFICATION forming part of Design No. 35,396, dated December 3, 1901.

Application filed October 24, 1901. Serial No. 79,884. Term of patent 14 years.

To all whom it may concern:

Be it known that I, HUGO L. HILLER, a citizen of the United States, and a resident of the borough of Manhattan, in the city and State 5 of New York, have invented and produced a new and useful original Design for a Shoe-Lacing, of which the following is a specification.

The essential feature of my design consists 6 in a shoe-lacing the body portion of which is broad and flat, the ends of said body portion being contracted into small cylindrical form and the tips being extended beyond the small cylindrical portions in the form of tassels.

5 The accompanying drawing represents the

shoe-lacing, the body being indicated by *a*, the contracted cylindrical portions of the outer ends of the body by *b b'*, and the tassels by *c c'*.

What I claim is—

The design for a shoe-lacing substantially as herein shown and described.

In testimony that I claim the foregoing as my invention I have signed my name, in presence of two witnesses, this 28th day of August, 25 1901.

HUGO L. HILLER.
